UNITED STATES PATENT OFFICE.

A. WHELAN, OF WASHINGTON, DISTRICT OF COLUMBIA, ASSIGNOR TO HIMSELF AND JOSEPH W. PARRISH, OF SAME PLACE.

IMPROVEMENT IN HINGES.

Specification forming part of Letters Patent No. 85,977, dated January 19, 1869.

To all whom it may concern:

Be it known that I, ALEXANDER WHELAN, of the city of Washington, in the county of Washington and District of Columbia, have invented a new and useful Improvement in Hinges for Window-Shutters and other similar uses; and I do hereby declare that the following is a full, clear, and exact description thereof, reference being had to the accompanying drawings and the letters of reference marked thereon, in which—

Figure 1 is a view of an open hinge made in accordance with my invention. Fig. 2 is a view of that part of the hinge which is attached to the window-frame; and Fig. 3 is a sectional view of that part of the hinge which is attached to the shutter in the line x, Fig. 1.

A is the part of the hinge to be attached to window-frame, and B the part to be attached to the shutter. C is the pivot on which the movable part of the hinge turns. i i' are helical inclined shoulders at the base of the pivot C. There are two opposite projections at the base of said pivot, each forming two inclined shoulders, i and i' , meeting at their upper extremities, and forming V-shaped points v and v' on said projections. The incline i is somewhat more inclined, and consequently somewhat longer, than the incline i' . The socket D in the part B, into which the pivot C fits, has at its base inclined helical shoulders j and j' , exactly corresponding in form with the inclined shoulders i i' of the pivot. The inclined shoulders of the pivot and the socket are so located that whenever the hinge is opened, so that the two wings A and B will be in the same plane, the socket will come down on the pivot to its base, forming a close joint. And so, again, when the shutter is thrown open, so as to close the leaves of the hinge one upon the other, the socket will fit down upon the base of the pivot in like manner, forming a close joint. Thus, the socket being closed at its upper end, and a perfectly tight joint being formed, whether the shutter be open or closed, no water can enter any part of the joint, to cause a rusting of the metal, or ice in

winter. The inclines of the pivot and socket are so arranged that when the shutter is thrown clear open against the wall, and the leaves, A and B of the hinge are in the same plane, the incline i of the pivot is in close contact with the incline j of the socket, and this will hold the shutter back against the wall until considerable force is applied to move it, thus obviating the necessity of any other fastening to hold the shutter against the wall. But when sufficient force is applied to overcome this resistance, the moment the shutter begins to turn on the hinge, the incline j of the socket will rise upon the incline i of the pivot, elevating the shutter, until the points of said inclines pass each other, at which time the shutter will begin to descend, the incline j of the socket sliding down on the incline i of the pivot; and said inclines are so arranged that the socket will drop clear down to the base of the pivot before the upper part of the shutter reaches the cap of the window-frame, and the shutter will swing home in the same plane, clearing said cap, none of the inclines coming in contact. In like manner, in opening the shutter, it will swing in the same plane, none of the inclines coming in contact until it has cleared said cap of the window-frame.

I do not limit my claim to this invention in its application to window-shutters, but claim its application to doors and gates.

I do not claim, broadly, the leaves of a hinge with the double set of inclines; but

What I do claim as new, and desire to secure by Letters Patent of the United States, is—

The combination and arrangement of the two sets of inclines i and i' and j and j' , with relation to the pivot and socket of a hinge, constructed as described, whereby the shutter is made to clear the window-frame before being raised by the said inclines.

A. WHELAN.
